Inventor:
JOHN F. RUTH,
By John H. Bunning,
His Attorney.

UNITED STATES PATENT OFFICE.

JOHN F. RUTH, OF ST. LOUIS, MISSOURI.

METAL WINDOW.

Application filed December 10, 1926. Serial No. 153,776.

This invention pertains to metal window construction.

One of the objects of this invention is to provide an improved window construction whereby the fit of the sash may be adjusted.

Another object is to provide an improved construction in which the friction of the sash is reduced.

Another object is to provide a construction which will conceal and protect the sash cord.

Another object is to provide an improved construction which will be cheap to manufacture and which may be adjusted to suit the peculiarities of each installation.

Another object is to provide an improved construction adapted to render the frame stiff so as to withstand lateral pressure of the sash.

20 Further objects will appear from the following description, taken in connection with the accompanying drawing, in which

Figure 1 is a vertical section showing a window embodying this invention;

25 Figure 2 is a section on line 2—2 of Figure 1;

Figure 3 is a perspective detail of the auxiliary jamb; and

30 Figure 4 is a perspective detail of the anchor for the inside stop fastening.

Referring to the drawing, Figure 1 shows a vertical section of the window and the frame, which comprises a lintel 1, a sill 2 and vertical jambs 3, only one of which is 35 shown in the drawing. The lintel 1 has a channel form provided with inner and outer flanges 4 and 5. This lintel is formed with an inwardly extending channel or groove 6 and adjacent thereto a downwardly extending flange or rib 7. The sill 2 has a channelled form, which may have any suitable shape, such as illustrated in Figure 1.

40 Each jamb 3 has a rectangular box form, as shown in Figure 2, and is provided with an inwardly extending flange 8. The outside of the box is closed by a plate 9, having an inwardly directed flange 10, which forms the outside stop which guides the upper sash. The plate 9 may be crimped to the jamb 3 45 on the outside, as shown at 11, and is also secured to the flange 8 by means of rivets 12 or other suitable fastening. A gutter 13 50 may be secured to the outer flange 5 of the lintel and run down the outside face of the

jamb, as illustrated in Figures 1 and 2. 55 The inner edge of the flange 10 forms the outer stop which guides the upper sash 14. The sash 14 may also be of metal and has its stiles formed with an outwardly extending rib 15 adapted to co-operate with the flange 10 to guide the sash. An inner guide for the rib 15 is provided by a flange 16 formed or mounted on an auxiliary jamb indicated generally at 17. The auxiliary jamb 17 has a generally channelled form 60 but is provided with an inwardly extending channel 18, running along the middle thereof. This channel is slightly wedge-shaped and encloses an inverted U-shaped channel 19, which serves to fill out the inner part of 65 the channel 18 and stiffen the same. From the channel 18, sloping webs 20 extend outwardly to both sides, terminating in right angle flanges 21. The flanges 21 are adapted to bear against the inner face of the jamb 70 3 and have mounted therein at intervals therealong adjusting bolts 22. The bolts 22 extend through sides of the jamb with the head of the bolt against one flange and accessible for adjustment while the nut is 75 80 against the other flange.

Mounted on the inner face of the channel 18 is a plate 23, whose edges are each bent or deflected at obtuse angles to form the flanges 16. The flanges 16 may be straight, 85 but, as shown in Figure 3, they taper so as to start at the middle of the jamb 17 and increase in width toward opposite ends, merging into the plate at the middle. The deflection of the flanges as well as their taper 90 is shown exaggerated, for in practice both will be slight.

The inner sash 24 is provided with a rib 15 similar to that described for the outer sash 14. This rib 15 engages the other 95 flange 16 of the auxiliary jamb and is, in turn, engaged by a flange 25 on an inner stop 26. The stop 26, as well as the other parts above mentioned, may be constructed of pressed sheet metal and has an outer 100 flange 27, which rests against the jamb 3, and an inner flange 28 which rests upon the edge of the auxiliary jamb 17 and serves to clamp the same against the jamb 3 while centered therein. The stop 26 is secured in 105 place by clamping bolts 29, having threaded engagement with clips 30 on the exposed face of the jamb. These clips are slipped

under the projecting ends of pairs of holding lugs 31, cut from the inner face of the jamb 3 and bent inwardly, as shown in Figure 4. This permits the stop to be adjusted 5 towards the sash, the clips sliding between the lugs. The auxiliary jamb has cut out portions to clear the clips, as shown in Figures 3 and 4.

The meeting rails of the sashes may be 10 provided with flanges 32 and 33, as illustrated in Figure 1. The upper rail of the outer sash is arranged to abut the flange 7 on the lintel when the sash is up. The top rail of this sash may be provided with an 15 upwardly extending flange 34, which enters the channel or groove 6 so as to provide a weather seal. The sash weights 35 may be connected by sash cords, running over pulleys 36 and connected to suitable fasteners 37 on the ribs 15. It will be noted 20 that the stops 10 and 26, together with the auxiliary jamb 17, form an enclosure within which the sash cords operate.

It will be noted that the sloping webs 20 25 give the auxiliary jamb an arched form with the bearing flanges 21 spaced laterally from the crown of the arch. This arched form with spaced bearing points gives great stiffness to withstand lateral pressure from the 30 sash in either direction. The bolt 22 serves to further brace and stiffen the arch. The plate 23 is carried by the arch and provides a parting stile between the upper and lower sash.

35 In assembling this window, the fit of the sashes may be adjusted by adjusting the auxiliary jamb 17. This is done by means of the bolts 22, before the stop 26 is in place. By drawing the flanges 21 together, the 40 plate is sprung towards the sashes, and by proper adjustment of these screws, the flanges may be sprung to cause them to bear evenly against the sash edges. The 45 flanges bear at their edges so as to not only reduce friction but also to scrape as little paint as possible from the metal of the sashes. It will be noted that these flanges bear against the corners between the sash edges and the ribs 15 so as to secure location 50 of the auxiliary jamb, which is retained by the flange 28 of the stop 26.

Where the flanges 16 taper from the middle to the ends of the jamb, any channel 55 38 formed will be closed; for by drawing together the sides by the bolts 22, the middle, where the flanges 16 disappear, will be brought into engagement with the edges of the sash. This provides a seal against the 60 passage of a draft through the space 38.

65 It will be seen that by the present construction not only is the window rendered weather-tight all around, but the moving parts are all housed so as to be hidden from view and protected against deterioration. Furthermore, the various parts are adjust-

able in such a way that a proper running fit may be provided between the sash and its guides and at the same time a weather-tight joint is provided.

It will also be noted that the portion 18 70 of the auxiliary jamb forms a parting style on which the bearing plate 23 is mounted. This parting style is relatively narrow while the auxiliary jamb has a broad bearing on the main jamb, so that a stiff and rigid 75 parting style is provided which is not subject to warping or distortion by the forces acting upon it.

It is obvious that various changes may be 80 made in details of construction without departing from the spirit of this invention; it is, therefore, to be understood that this invention is not to be limited to the specific details shown and described.

Having thus described the invention, what 85 is claimed is:

1. A metal window frame having a sash therein provided with a rib, a jamb having a part engaging the edge of said sash along said rib, a stop engaging the opposite side 90 of said rib along said sash, and means for adjusting the engaging part of said jamb towards said sash.

2. A metal window frame having sashes therein each provided with a rib, a jamb having parts engaging the edges of said sashes along said ribs, stops engaging the 95 opposite sides of said ribs along said sashes, and means for adjusting the engaging parts of said jamb towards said sashes.

3. A metal window frame having a sash provided with a cord, a jamb bearing against the edge of said sash, means for adjusting said jamb towards said sash, and a stop bearing against said sash and forming with said 105 jamb an enclosure for the cord.

4. A metal window frame having a sash, a stop bearing against said sash, clips adjustable on the jamb face of said frame, and means for mounting said stop on said clips. 110

5. In a metal window frame having a sash, an adjustable jamb having spaced sides, a bearing therealong, and means connecting said sides and accessible at the outer face of one of said sides for drawing said sides 115 together.

6. In a metal window frame having a sash, an adjustable jamb having spaced sides, a bearing therealong, and bolts passing through said sides for drawing them together. 120

7. In a metal window frame having a sash, an adjustable jamb having spaced sides, and a bearing plate therealong and provided with a deflected edge for engaging the sash. 125

8. In a metal window frame having a sash, an adjustable jamb having spaced sides, a bearing plate therealong and provided with a deflected edge for engaging the sash, and means for drawing said sides together. 130

9. In a metal window frame having a sash, a jamb having a bearing plate therealong provided with a deflected edge for engaging the sash.
- 5 10. In a metal window frame having a sash, a jamb having a bearing plate therealong provided with a sash engaging edge which is gradually deflected along the plate.
11. In a metal window frame having 10 sashes, a jamb having a bearing plate therealong whose edges are deflected to engage the sashes.
12. A metal window frame having a sash therein provided with a rib, a jamb having 15 a part engaging the edge of said sash along said rib, a stop engaging the opposite side of said rib along said sash, means for adjusting the engaging part of said jamb towards said sash, and means for adjusting 20 said stop towards said sash.
13. A metal window frame having sashes therein provided with ribs, an auxiliary jamb with stops located on the frame and engaging ribs, and adjustable means for engaging 25 said sashes adjacent said ribs and adapted to limit the lateral movement of said sashes.
14. A metal window frame having sashes therein, provided with ribs, an adjustable 30 auxiliary jamb, stops located on the frame engaging said ribs, and said auxiliary jamb carrying extended means for engaging said ribs and adapted to limit the lateral movements of said sashes.
- 35 15. A metal window frame having sashes therein, provided with ribs, an adjustable auxiliary jamb, stops located on the frame engaging said ribs, and said auxiliary jamb carrying adjustable extended means for engaging 40 said ribs and adapted to limit the lateral movements of said sashes.
16. A metal window frame having a sash therein provided with a rib, and a jamb having a deflected edge engaging said rib.
17. A metal window frame having a sash 45 therein provided with a rib, and a jamb having a deflected edge engaging said rib, a portion of said jamb edge being un-deflected.
18. A metal window frame having a sash 50 therein provided with a rib, and a jamb having a variably deflected edge engaging said rib, a portion of said jamb edge being un-deflected.
19. A metal window frame having a jamb, a parting style along said jamb, supporting 55 elements for said style spaced laterally therefrom and means for bracing said supporting elements.
20. A metal window frame having a jamb, a parting style along said jamb having a 60 bearing on said jamb of greater lateral extent than said style and a thrust supporting element between said stile and said bearing.
21. A metal window frame having a jamb, and an auxiliary jamb mounted on said 65 jamb and having a parting stile therealong, said auxiliary jamb having a wide bearing along said jamb and being formed to transmit a thrust from said stile to said bearings.
22. A metal window frame having a jamb, and an auxiliary jamb mounted on said 70 jamb and having a parting stile therealong, said auxiliary jamb having a wide bearing along said jamb and being arched so as to transmit lateral pressure from said stile to 75 said bearing.
23. A metal window frame having a jamb, a parting stile along said jamb, supporting 80 bearings for said stile spaced laterally therefrom, and means adapted to maintain the spacing of said stile and said bearings.

In testimony whereof I affix my signature this 24th day of November, 1926.

JOHN F. RUTH.
